UNITED STATES PATENT OFFICE.

IRA ANDREW POWELL, OF ST. LOUIS, MISSOURI.

GASKET-MAKING MACHINE.

1,205,782.

Specification of Letters Patent. Patented Nov. 21, 1916.

Application filed March 13, 1916. Serial No. 83,883.

To all whom it may concern:

Be it known that I, IRA A. POWELL, a citizen of the United States, and a resident of St. Louis, in the State of Missouri, have 5 invented a certain new and useful Improvement in Gasket-Making Machines, of which the following is a specification.

One of the principal objects of my invention is to provide an improved machine 10 for making gaskets or washers, incorporating means for shaping the gaskets, stamping or compressing the same, and then removing them from the die.

Another object of the invention is to provide 15 a gasket making machine which will be extremely simple, durable, efficient in operation, and inexpensive to manufacture.

With these and other objects in view which will become apparent as the description 20 proceeds, the invention resides in the construction, combination, and arrangement of parts hereinafter more fully described and claimed, and illustrated in the accompanying drawings in which like characters 25 of reference indicate like parts throughout the several figures, of which—

Figure 1 represents a view in front elevation of a gasket machine constructed according to my invention. Fig. 2 represents 30 a side elevational view thereof. Fig. 3 represents a view in section taken horizontally on the plane indicated by the line 3—3 of Fig. 1. Fig. 4 represents a fragmentary view partially in section, showing the position 35 of the parts after the gasket has been shaped on the die. Fig. 5 represents a view similar to Fig. 4, showing the position of the parts at the completion of the compressing operation.

Referring more particularly to the drawings, the machine includes a pair of spaced 40 vertically extending parallel standards 5, which may be formed of lengths of I-beam, the standards being secured by means of angles 6 to the floor of the shop, and at 45 their upper ends being connected together by means of plates 7. Secured by means of angle irons or brackets 8 to the uprights 5, is a horizontally arranged table or plate 9. It is partly supported by means of the 50 legs 10 secured at their upper ends to the table, and at their lower ends bolted or otherwise fastened to the floor. The table is provided with an opening 11, through 55 which a die 12 carried on the upper end of a vertical shaft 13 is adapted to pass. This shaft 13 is slidably and rotatably journaled

in a bearing 14 carried by the uprights 5 beneath table 10, and the shaft has a bevel gear 15 slidably keyed thereon, said gear 60 being supported upon a cross piece 16 carried by the legs 10. A bearing 17 secured to the cross piece, slidably receives the shaft 13. A spring 18 interposed between the lower end of the shaft and the floor normally 65 maintains the shaft at the upper end of its path of movement, so that the guide 12 will be positioned above the table 10.

A horizontally arranged main shaft 19 is journaled in bearings 20, between the uprights 5 near their upper ends, and is adapted to be coupled by means of a clutch 21 with a pulley 22 driven by means of a belt 23 from a suitable source of power. A pulley 24 operated from the pulley 22 drives 70 a belt 25, which in turn drives a pulley 26 carried on a shaft 27 which is journaled adjacent the lower ends of the standards 5 in bearings 28. This shaft 27 carries a pinion 29 which meshes with the pinion 15, whereby 75 the die 12 may be driven in a rotary manner.

A crank arm 30 carried on the shaft 19 is connected by an adjustable rod 31, with a pin 32 carried by a vertically arranged 80 squared rod 33 which is guided for reciprocation in bearings 34 carried by the uprights 5. The adjustable rod 31 comprises segments connected by a turnbuckle 35 which may be operated for drawing the segments toward each other, or for shifting them apart. In this manner, the path 85 through which the pilot 36 carried at the lower end of rod 33 reciprocates, may be varied. The pilot 36 is circular, being arranged above the die 12, and is tapered at its lower end as at 37. A circular flange 38 is carried near the upper end of the pilot.

A stripper 39 in the nature of a plate having an opening therein through which the 100 pilot 36 may project, and having upstanding arms 40 at its rear portion, which arms lie against the uprights 5, is provided. The arms 40 of the stripper have slots 41 cut therein, and bolts 42 carried one by each of 105 the uprights 5 project through these slots and guide the stripper in its up and down movements. A lever 43 having a bifurcated inner end between the prongs of which a corrugated roller 44 is journaled, is pivoted 110 as at 45 to the table or plate 9. The lever 43 may be moved in one direction or the other, for bringing said roller 44 toward or away from the die 12. This die is circum-

ferentially corrugated, as is also the roller 44, and the corrugations of the latter are arranged alternately with the corrugations of the die, so as to fit therein when the 5 roller is moved into engagement with the die.

The clutch 21 is adapted to be operated by means of a long lever 46 pivoted on a bracket 47 carried by one of the uprights, 10 and connected at its lower end as at 48 with a link 49 suitably secured to one of the uprights. This link may be shifted forwardly or rearwardly for throwing the clutch into or out of gear, and in order to facilitate 15 this operation, the link is provided with a handle 50 which may be grasped by the operator.

In forming a gasket, a strip of rubber 20 textile or other material, is cut to a desired length and width, and is then formed into a loop, the ends of the strip having been previously cut crosswise at an angle so as to form beveled ends, and these ends are then cemented or otherwise fastened together, so that the joint will extend across 25 the ring thus formed at an angle. While in this circular form, the gasket or ring is placed over the die 12, and the roller 44 is then pressed against it. The die is rotated, 30 by the means already described, and as the roller is pressed against the ring or band, the latter is pressed into the corrugations of the die to take the shape indicated at 35 51 in Fig. 4. The roller is then moved away from the die, and the clutch 21 thrown in, 40 whereby the pilot 36 is caused to move downwardly, carrying with it the stripper 39, and in engaging upon the die 12, forces the latter downwardly, against the tension of 45 the spring 18, and as the gasket 51 engages against the upper face of the table or plate 9 around the edge of the opening 11, the corrugations of the gasket become pressed together and the gasket is properly shaped, 50 as the pilot 36 moves therethrough toward the completion of its downward stroke. It is to be noted that the diameter of the pilot at its lower end is substantially coincident with the diameter of the upper portion of 55 the die 12, so that as the die moves downwardly, the gasket in being arrested by the table 9, will be slipped up onto the pilot. On the upward stroke of the rod 33, as the revolution is completed, the pilot moves upwardly, carrying with it the gasket 51, and at the same time the stripper 39 will move 60 upwardly, since the engagement of the gasket with the pilot will support the stripper, but as the stripper reaches the limit of its upward movement, the continued upward movement of the pilot, will cause the gasket to be stripped from the pilot so that it may be removed from the machine. The spring 18 returns the die to its normal position.

Although I have described the preferred

embodiment of my invention, I may desire to make such changes in the construction, combination, and arrangement of parts thereof, as do not depart from the spirit of the invention and the scope of the appended 70 claims.

I claim:—

1. A gasket machine including a pair of spaced uprights, a table carried thereby and having an opening therein, a vertically arranged shaft having a die extending through the opening and normally retained in position above the table, means being provided for returning the die to normal position after displacement therefrom, means for rotating said die, a roller, a lever on which the roller is carried, said lever being pivoted to the plate, in position to be shifted for moving the roller against the die, whereby to impart to an unfinished 85 gasket the formation of the die, a main shaft, means for rotating the latter at will, a vertically arranged rod, bearings carried by the uprights through which the rod is slidably supported, connecting means between the main shaft and the rod whereby the latter may be reciprocated as the shaft is rotated, a cylindrical pilot having a tapered lower end and having an outstanding 90 flange at its upper end connected with said vertical rod, said pilot being at its lower end of a diameter substantially coincident with the diameter of the die, and a stripper comprising a horizontally arranged plate having an opening therein of a diameter 95 substantially equal to the diameter of the pilot, said stripper being arranged below the pilot and being provided with upwardly extending arms having slots provided therein, 100 bolts carried by the uprights and extending through said slots for guiding the stripper and for limiting its movement, substantially 105 as described.

2. A gasket machine including an upright member having a horizontally arranged table carried thereby, said table being provided with an opening, a die arranged normally above the table and movable through the opening, resilient means for returning the die to normal position after displacement therefrom, said die being of a diameter substantially equal to the diameter of the opening in the table, means for rotating the die, a roller, means whereby the roller may be moved into and out of engagement 115 with the die whereby an unfinished gasket may be shaped against the die, a pilot arranged above the die, means whereby the pilot may be separately operated in vertical position at will, and a stripper having 120 an opening through which the pilot may be projected as it is moved downwardly, and means for stopping the upward movement of the stripper prior to the arrival 125 of the pilot at the upper terminus of its 130

path of movement, for stripping the gasket from the pilot.

3. A gasket making machine, including a table, a die arranged above the table and adapted to be vertically reciprocated through an opening provided in the table, said opening being of a diameter substantially equal to the diameter of the die, means for compressing an unfinished gasket 5 against the die whereby to impart the configuration of the die to the gasket, a pilot arranged above the die, said pilot being of a diameter substantially equal to the diameter of the die, means whereby the 10 pilot may be vertically reciprocated for moving the die through the opening in the plate, resilient means for returning the die to its normal position, a stripper arranged between the die and pilot and having an 15 opening through which the pilot is projected when moved downwardly, said pilot being provided with a flange for engaging the stripper whereby to move the latter downwardly with the pilot, and means for 20 limiting the upward movement of the stripper prior to the arrival of the pilot at the upper end of its path of movement, whereby to strip the gasket from the pilot.
4. A gasket making machine including a table having an opening therein, a circumferentially corrugated cylindrical die arranged above the plate in alinement with the opening and adapted to be shifted downwardly through said opening, means for 25 turning the die to its normal position, means for rotating said die, a circumferentially corrugated vertically arranged roller adapted to be moved toward and away from the die for imparting the configuration of the 30 die to an unfinished gasket arranged on the die, a pilot arranged above the die, means for reciprocating the pilot in a vertical path at will, for driving the die through the opening in the plate whereby to compress the 35 unfinished gasket against said plate, said pilot at its lower end being of a diameter substantially coincident with the diameter of the die whereby the pilot may advance through the gasket for imparting the proper 40 internal diameter thereto, and means for 45 stripping the gasket from the pilot as the latter moves upwardly.
5. A gasket forming machine including a circumferentially corrugated die, means for 50 rotating the die, a vertically arranged circumferentially corrugated roller, means whereby said roller may be moved toward and away from the die for compressing an unfinished washer against said die whereby 55 to impart the formation of the die to the washer, a plate having an opening therein through which the die may be forced for 60
- arresting the washer against the plate, a pilot arranged above the die, means for reciprocating the pilot whereby the washer 65 may be compressed against the plate, the pilot being substantially of a diameter equal to the diameter of the die for imparting the proper diameter to the washer, and means for stripping the washer from the pilot as 70 the latter moves upwardly.
6. A gasket making machine including a die, adapted to receive an unfinished washer, a roller, means for moving said roller toward and away from the die whereby the washer 75 may be compressed against the die at will to impart the proper formation to the washer, a plate having an opening through which the die may be reciprocated for arresting the gasket against the plate, means for compressing the gasket against the plate, and means for stripping the gasket from the 80 compressing means.
7. In a gasket making machine, a die, means for compressing an unfinished gasket 85 thereagainst whereby to corrugate the gasket, a plate having an opening therein through which the die may be reciprocated whereby to strip the gasket from the die, and rest the gasket against said plate, means 90 for compressing the gasket against the plate, and means for removing the gasket from the compressing means.
8. In a gasket making machine, a die having circumferentially extending corrugations provided thereon, said die adapted to receive an unfinished gasket, a circumferentially corrugated roller, means for moving said roller at will toward the die for imparting the corrugated formation of the die to 95 the unfinished washer, a plate having an opening therein through which the die registers, means for forcing the die through the opening to rest the gasket against the plate and to simultaneously compress the gasket, 100 and means for stripping the gasket from the last said means.
9. A gasket making machine including a plate having an opening therein, a die movable through the opening and adapted to receive an unfinished gasket, means for forming the gasket about the die to impart the correct formation to the gasket, a pilot adapted to engage the die for moving the die through the opening in the plate whereby to strip the gasket from the die and arrest the gasket plate, said pilot being provided with means for compressing the gasket against the plate, and means for removing the gasket from the pilot.
